FOOT WARMER

Elisha Starr Winn, Sr., Fitzgerald, Ga.

Application June 11, 1946, Serial No. 675,895

5 Claims. (Cl. 219—19)

1

This invention relates to a foot warmer and has for its object to provide a foot warmer which is very inexpensive and simple in construction and operation, and utilizes not more than two specially made parts in combination with other parts of standard construction readily available on the market.

A further object of this invention is to provide a foot warmer of the type shown in the U. S. Patent to Smith No. 1,545,858, but which is much more simple and inexpensive to manufacture and assemble.

A still further object of this invention is to provide a foot warmer utilizing a majority of standard parts which are readily and inexpensively available on the market.

Yet a further object of this invention is to provide a one-piece spring clamp for holding a conventional electric light bulb and socket within an ordinary fruit or Mason jar, with the wires to the bulb extending through an insulating grommet in the jar cover or through an opening in the cover made entirely of insulation material.

A still further object of this invention is to provide a bulb and socket holding one-piece clamp which may be used by anyone in assembling a footwarmer of readily available materials and parts, by merely combining the clamp with a bulb and socket connected by wires to a source of electricity, and a Mason or fruit jar and cover by making a hole through the cover for the wires to pass through, possibly taping the wires to protect and insulate them at the point the wires pass through the hole in the cover.

A further object of this invention is to provide means for sustaining the electric socket and heating element, which heating element may be a lamp bulb; at about mid-point within the jar without the socket and heating element being solidly attached to the cap of the jar, thereby assuring uniform temperature within the jar and uniform temperature of each end of the jar.

With all of the above mentioned objects and advantages of the invention in view, I have disclosed in the accompanying drawing forming a part of this specification an embodiment of the foot warmer made in accordance with the principles of the present invention, and in the drawing—

Fig. 1 is a perspective view of the invention in use;

Fig. 2 is an elevational view, partly broken away, of the assembled foot warmer;

2

Fig. 3 is a perspective view of the spring clamp of this invention; and

Fig. 4 is a sectional view on line 4—4 of Fig. 2.

There is shown at 10 the light bulb and bulb socket holding spring clamp of this invention. This clamp 10 consists of a pair of arms 11 integrally joined together by a substantially semi-circular cross arm 12 which continues beyond the arms 11 in the form of curved spring fingers 13 whose ends are slightly spaced apart; thus forming almost a complete circle. The inside diameter of the curvature of the cross arm 12 and the curved fingers 13 is about equal to or slightly less than the outside diameter of the neck 15 of a standard light bulb socket 16 so that they may be temporarily sprung apart and then embrace and securely hold such a socket 16 therebetween.

The arms 11 are offset at 17 from the cross arm 12 so as to extend substantially in parallel along the sides of the socket 16 and then extend a suitable length, and on the other side of the cross arms 12, the arms 11 flare outwardly from each other as at 18, the overall length of the arms 11 being substantially equal to the inside length of the Mason or fruit jar 20 in which the invention is used. This conventional fruit jar 20 is of any standard size, such as a quart, two-quart, or gallon size, and the clamp 10 may be made in different sizes for different jars, or a large sized clamp may be cut down to fit a smaller jar by clipping off the ends at appropriate distance. A hole 21 is cut through a jar cover 19 and may be provided with an insulation grommet 22, or alternatively insulation tape may be wound around the wires 23 where they extend through the cover and lead from the socket 16 to the plug 24 for connection to any standard electric receptacle 25. If the cover 19 happens to be of an insulating material, such as a plastic material or Bakelite or the like, only a smoothly round hole is needed therethrough.

In operation, the foot warmer provided by this invention is intended for use in a bed as shown in Fig. 1. A conventional socket 16 has its neck 15 inserted between the curved spring fingers 13 of the clamp 10; the wires 23 being passed through the opening 21 of a fruit jar cover 19, insulated by the grommet 22 or by tape, if necessary, if the cover does not already happen to be made of Bakelite or the like insulation material. A lamp bulb 26, preferably 7½-watts, in the socket 16, provides the necessary warmth when placed within the fruit jar 20. The cover 19 placed on the fruit jar 20 presses against the

ends of the parallel arms of the clamp 10, causing the flared arms 18 to yieldably press against the inside of the bottom of the jar, thus holding the clamp firmly in place within the closed jar, ready for use as shown in Fig. 1.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

What is claimed is:

1. For use in a foot warmer having a heating element; an electric socket holding clamp of resilient material adapted to be placed in a standardized container of the fruit jar type, the container having a removable cover which may be perforated to permit electric wires to the socket to extend therethrough, said clamp comprising a pair of arms flaring somewhat outwardly from about their mid-point and being longer than the internal height of the container, a semi-circular cross arm integrally securing said pair of arms together at about their mid-point, and a pair of curved fingers on said arms circumferentially aligned with said semi-circular cross arm, the diameter of the arcuate curve provided by said cross arm and curved fingers being not greater than the diameter of the neck of the electric socket.

2. A foot warmer comprising a heating element electric socket holding clamp of resilient material in combination with a container of the fruit jar type, the container having a removable cover perforated to permit electric wires to the socket to extend therethrough, said clamp comprising a pair of arms, a semi-circular cross arm integrally securing said pair of arms together at about their mid-point, and a pair of curved fingers on said arms circumferentially aligned with said semi-circular cross arm, the diameter of the arcuate curve provided by said cross arm and curved fingers being not greater than the diameter of the neck of the electric socket, said pair of arms being of an overall length to extend from the inside of the bottom of the container to the inside of the closed cover of the container and to resiliently press thereagainst when the cover is in closed position.

3. A foot warmer comprising a heating element electric socket holding clamp of resilient material in combination with a container of the fruit jar type, the container having a removable cover perforated to permit electric wires to the socket to extend therethrough, said clamp comprising a pair of arms, a semi-circular cross arm integrally securing said pair of arms together at about their mid-point, and a pair of curved fingers on said arms circumferentially aligned with said semi-circular cross arm, the diameter of the arcuate curve provided by said cross arm and curved fingers being not greater than the diameter of the neck of the electric socket, said pair of arms being of an overall length to extend from the inside of the bottom of the container to the inside of the closed cover of the container and to resiliently press thereagainst when the cover is in closed

position, the bottom ends of said pair of arms being flared toward the sides of the container.

4. A foot warmer comprising a heating element electric socket holding clamp of resilient material in combination with a container of the fruit jar type, the container having a removable cover perforated to permit electric wires to the socket to extend therethrough, said clamp comprising a pair of arms, a semi-circular cross arm integrally securing said pair of arms together at about their mid-point, and a pair of curved fingers on said arms circumferentially aligned with said semi-circular cross arm, the diameter of the arcuate curve provided by said cross arm and curved fingers being not greater than the diameter of the neck of the electric socket, said pair of arms being of an overall length to extend from the inside of the bottom of the container to the inside of the closed cover of the container and to resiliently press thereagainst when the cover is in closed position, the bottom ends of said pair of arms being flared toward the sides of the container.
5. A foot warmer comprising a heating element electric socket holding clamp of resilient material in combination with a container of the fruit jar type, the container having a removable cover perforated to permit electric wires to the socket to extend therethrough, said clamp comprising a pair of arms, a semi-circular cross arm integrally securing said pair of arms together at about their mid-point, and a pair of curved fingers on said arms circumferentially aligned with said semi-circular cross arm, the diameter of the arcuate curve provided by said cross arm and curved fingers being not greater than the diameter of the neck of the electric socket, said pair of arms being of an overall length to extend from the inside of the bottom of the container to the inside of the closed cover of the container and to resiliently press thereagainst when the cover is in closed position, the bottom ends of said pair of arms being flared toward the sides of the container, the pair of arms being offset just above said cross arm to substantially parallel portions spaced apart a distance at least as great as the diameter of the body of the socket and of the electric heating element carried thereby.
6. A foot warmer comprising a heating element electric socket holding clamp of resilient material in combination with a container of the fruit jar type, the container having a removable cover perforated to permit electric wires to the socket to extend therethrough, said clamp comprising a pair of arms, a semi-circular cross arm integrally securing said pair of arms together at about their mid-point, and a pair of curved fingers on said arms circumferentially aligned with said semi-circular cross arm, the diameter of the arcuate curve provided by said cross arm and curved fingers being not greater than the diameter of the neck of the electric socket, said pair of arms being of an overall length to extend from the inside of the bottom of the container to the inside of the closed cover of the container and to resiliently press thereagainst when the cover is in closed position, the bottom ends of said pair of arms being flared toward the sides of the container, the pair of arms being offset just above said cross arm to substantially parallel portions spaced apart a distance at least as great as the diameter of the body of the socket and of the electric heating element carried thereby, the heating element being a comparatively small lamp bulb.
